UNITED STATES PATENT OFFICE

2,002,759

INTERNAL COMBUSTION ENGINE

Esau Workman, Corcoran, Calif.

Application September 26, 1933, Serial No. 691,028

4 Claims. (CL 74—50)

This invention relates to an improved construction for internal combustion engines.

The invention comprises a number of valuable improvements which may be in general grouped under two heads, (1) an improved valvular means for controlling the supply of explosive discharge and the scavenging of the piston cylinders, and (2) an improved means for connecting cooperating pistons together and for transmitting the power which they generate to a common crank shaft.

One object of the invention is to provide a construction wherein the movements of the pistons are so timed with relation to the valves which control the intake and exhaust that ample time will be provided for an efficient scavenging without lessening the efficiency of the power production of the engine.

Another object of the invention is to provide a smoothly running mechanical movement feature which will enable the individual piston cylinders of the engine to cooperate in a more effective manner. In regard to this feature of the apparatus a series of improved cam members and cam operating parts to cooperate with them are provided.

Still another object of the invention is to provide an arrangement of piston cylinders and cooperating pistons therein which will function in such a manner as to guard against the piston cylinders being overheated, but will nevertheless contain a sufficiently rapid movement of the pistons to maintain efficient power production.

Other objects, advantages and features of the invention may hereinafter appear.

Referring to the accompanying drawings which illustrate what is at present deemed to be a preferred embodiment of the invention,

Fig. 1 is a longitudinal vertical section of the engine showing three out of the four sets of piston cylinders and their cooperating parts. This view is sectioned on line 1—1 of Fig. 4.

Fig. 2 is a cross section taken on line 2—2 of Fig. 1.

Fig. 3 is a view on line 3—3 of Fig. 1 showing the parts in a different working position. The upper and lower portions of the plane of section coincide with the plane on which Fig. 2 is sectioned.

Fig. 4 is a top plan view of the complete structure except that parts of the piping are broken away. A bottom plan view would present a similar appearance.

Fig. 5 is a section of the crank shaft illustrat-

ing the relative positions of the crank portions thereof.

Referring in detail to the drawings, in Fig. 1 is shown an engine frame or casing 10 which forms a supporting means, and to opposite sides of which are secured the engine cylinders. To one side of this frame are secured the piston cylinders 11 which are arranged in spaced parallel relation to each other, and to the opposite side of said casing 10 are secured the piston cylinders 12 each of which is located in alignment with a piston cylinder 11 thus providing for sets of aligned cooperating pistons. Within said piston cylinder 11 is located a cylindrical piston 13 and within each cylinder 12 is located a cylindrical piston 14. Hence there is opposite to each cylindrical piston 13 a cooperating cylindrical piston 14.

The aligned pistons 13 and 14 are rigidly connected together by rods 15 which, together with the cross rods 16, form rigid driving frames, one frame for each group of four cooperating pistons. The crank shaft 17 is located centrally with relation to the piston cylinders of each group and the crank portion 18 thereof (Fig. 3) which cooperates with each group of pistons has rotatably mounted upon it a rotor 19. Around said rotor 19 is extended a cam carrying driven frame 20, said frame having mounted upon each side thereof, or formed as an integral part of it, an elliptical cam element 21 which has in spaced relation to its rim portion a central member 22 mounted upon the cam by means of a web 23. Between each central member 22 and the outer portion of the cam element 21 of which it forms a part is an endless raceway 24. Each raceway 24 is engaged by a stub shaft 25 which projects from the frame bar 15 at that side of the structure. These raceways are elliptical and their long axes extend at substantially a right angle to the direction in which the pistons reciprocate. During operation the engine cylinders reciprocate the stub shafts 25 vertically and thereby also move up and down the entire cam supporting structure or frame 20. Simultaneously with this up and down movement said frame 20 is given a lateral oscillation by reason of its operative connection with the crank shaft, which will next be described.

The cam frame 20 carries two laterally projecting stub shafts 20a which are oppositely disposed with relation to the center of said frame. Each of these stub shafts has mounted upon it an anti-friction roller 20b. Between these rollers is fitted with a working fit the rotor 19 which is carried by one of the crank portions 18 of the crank shaft 17.

It is to be understood that, owing to the fact

that the engine is provided with three cooperating groups of pistons, each group having therein four pistons, it is possible to arrange the cam structure which has been described in such a manner that there will be a uniform effective transmission of power from the engine cylinders to the crank shaft.

Means will next be described for controlling the intake ports and exhaust ports of the engine. 10 The intake pipe 29 of each cylinder communicates with an intake port 30, and there is also provided for the cylinder an exhaust port 31 which communicates with the exhaust pipe 32. Within each piston cylinder 11, or 12, is mounted a sleeve 15 valve 33 which is necessarily in alignment with the corresponding valve at the opposite side of the crank casing. Each of these sleeve valves is provided with an arm 34 connected therewith in an offset manner. These arms 34 are in turn 20 united by a cam-surrounding frame 35. Fixed to the crank shaft and located within this frame is the cam element 36 which, through the cam guide members 37 carried by said frame, causes the rotation of the crank shaft to reciprocate the cam-surrounding frame vertically, thus operating the 25 valves which control the intake and exhaust.

The upper sleeves 33 travel to the firing position (see Fig. 2) and they remain stationary at this point and act as a motor head while the crank turns 70° further. Then sleeves 33 travel downwardly during a further crank movement of 80°. This brings the port hole 44 in sleeve 33 from alignment with the spark plug to the exhaust position and thus completes the charged stroke 30 of one side.

Meanwhile the opposing side has been performing the opposite cycle as follows: The lower two sleeves 33 travel with the crank while the latter turns 30° and then stand still thus holding the head 14 in the exhaust position while the crank advances 70° and forces a complete scavenge by the time the crank reaches the 280° position. Then sleeve 33 again starts to move and continues to do so until it closes the exhaust port 44, the 40 crank, during this time, advancing 80° to the 360° position and forcing out the explosive mixture which now goes through the check valve 39 into the sleeve 33. Thus the travel of the crank shaft from the 280° to the 360° position has caused the 45 sleeve 33 to close the exhaust and intake and compress the explosive mixture within the cylinder 12.

The explosive mixture does not enter the sleeve 33 while the contents of said sleeve is being fired or scavenged. The explosive mixture is forced through the bypass valve 39 in the head of sleeve 33 from the inside of outside cylinder 11 or 12 to the inside cylinder or sleeve 33 as the piston and sleeve travel up, or out, after the sleeve has 50 paused at 280° until the piston has reached the head of the sleeve 33 and completely scavenged itself. This type of engine has a four point crank-

shaft firing order with two pairs of pistons in consecutive unison, upon their respective travel to firing points.

Referring to certain preferred details of construction the crank webs 45a and 45b, integral with the crank shaft 17 and its crank portions 18, are provided to reinforce the structure while maintaining it in a compact form. The structure just described provides an efficient means for securing the rotor 19 upon the crank portion 18, as 10 shown in Fig. 1.

Two carburetors C are provided, the uppermost of which is shown in Fig. 4.

I claim:

1. In an engine, a group of piston cylinders which are arranged in pairs, the cylinders which compose each of said pairs being in a parallel spaced relation to each other, supporting means whereon said cylinders are mounted, a piston rod frame, pistons carried by said frame, a piston being thus provided for each of said cylinders, a crank shaft having a crank portion, a rotor mounted on said crank portion, a frame having a central portion in an operative relation to said rotor, said frame having raceways at opposite 25 sides of said rotor, and means mounted upon said piston rod frame to travel along said raceways and thereby actuate the last recited frame and rotate said shaft, said raceways being elliptical in shape and having their long axes directed at 30 substantially right angles to the direction of the reciprocation of said piston rod frame.

2. In an engine, a group of piston cylinders which are arranged in pairs, the cylinders which compose each of said pairs being in parallel spaced 35 relation to each other, supporting means whereon said cylinders are mounted, a piston rod frame, pistons carried by said frame, a piston being thus provided for each of said cylinders, a crank shaft having a crank portion, a rotor mounted on said 40 crank portion, a frame having a central portion in an operative relation to said rotor, said frame having endless raceways at opposite sides of said rotor, and stub shafts on said piston rod frame operatively engaging said raceways.

3. In a mechanical movement structure, a reciprocating driving frame, means to support said frame and guide it during reciprocation, a crank shaft having a crank portion, a rotor mounted on said crank portion, and a driven frame operatively related to said rotor, said driven frame having at opposite sides of said rotor endless raceways and said driving frame having stub shafts which engage said raceways whereby the reciprocation of said driving frame causes a gyroscopic 50 movement of said driven frame to gyrate said rotor and rotate said shaft.

4. The subject matter of claim 3 and, said raceways being elliptical with their long axes extending at substantially a right angle to the direction in which said driving frame reciprocates.

ESAU WORKMAN.
